Primary Examiner — Mary Ann Calabrese(74) *Attorney, Agent, or Firm* — Cantor Colburn LLP**CLAIM**

I claim, the ornamental design for a display screen or portion thereof with graphical user interface, as shown and described.

DESCRIPTION

The FIGURE is a front elevation view of a display screen or portion thereof with graphical user interface showing my new design.

The short dash-dash broken lines within the FIGURE illustrate unclaimed portions of the graphical user interface and the dot-dash broken line around the FIGURE shows the display screen; the broken lines form no part of the claimed design.
